CHARLES C. STUTZ, OF NORWOOD, OHIO, AND ROBERT F. ARNOTT, OF UPPER MONTCLAIR, NEW JERSEY, ASSIGNEES TO I. L. MYERS, OF NEW YORK, N. Y.

CLOSURE FOR PAPER PACKAGES.

1,207,657.

Specification of Letters Patent.

Patented Dec. 5, 1916.

Application filed May 3, 1913, Serial No. 765,224. Renewed October 12, 1916. Serial No. 125,289.

To all whom it may concern:

Be it known that we, CHARLES C. STUTZ a citizen of the United States, residing at Norwood, Hamilton county, Ohio, and ROBERT F. ARNOTT, a subject of the King of Great Britain, residing at Upper Montclair, Essex county, New Jersey, have invented a new and useful Closure for Paper Packages, of which the following is a full, 10 clear, and exact description, reference being had to the accompanying drawings, forming part of this specification, in which—

Figure 1 is a partial central vertical section showing one form of our invention; 15 and Fig. 2 is a similar view showing another form thereof.

In paper or similar cartons or packages it has been found difficult to satisfactorily close the hole in the cap or top closure of the 20 article.

In the drawings, referring to the form of Fig. 1, 2 represents the body of the carton or package, which is preferably cylindrical. 25 3 is an end closure having a flanged portion 4 cemented or otherwise secured to the inner surface of the carton body. The cap 3 is provided with a central hole, which we close by means of a hollow plug 5, which is preferably formed of paper material 30 drawn or struck up into plug shape. This plug preferably projects downwardly into the cavity below the cap, and is also preferably provided with a flange 6 resting on the top of the cap. The plug may be secured by 35 friction alone, or may be held by paraffin or other cement if desired.

In addition to the closure cap with the hole and plug, we may employ an additional 40 protecting disk and closure such as shown in Fig. 2. In this form we show the same parts as in Fig. 1, except that the cap 3^a is

pushed farther within the end of the body 2^a. In this case a flat disk 7, preferably of paper or pasteboard, is pushed within the end of the body of the carton, and prefer- 45 ably against the flange 4^a of the cap. The end portion of the cylinder is then pressed or spun over against the flat disk as shown at 8, to securely hold the parts in position. In this case, the plug 5^a may be the same 50 as in the first form.

The advantages of our invention result from the improved type of closure for the hole in the package cap. The plug closure may be cemented in place or held by fric- 55 tion, or by any other desirable means.

We claim:

A paper carton having a body portion, a cap having an outwardly extending flange seated in the end of said body portion, said 60 cap having an annular opening therein, a hollow plug seated within said opening, said plug having an annular flange arranged to engage the outer face of the cap, and a flat disk seated within the end of the body por- 65 tion on the flange of the cap, the end of the body portion being turned upon itself and forced into engagement with the disk, so that the disk is retained between the flange 70 of the cap and said turned portion; sub- stantially as described.

In testimony whereof, we have hereunto set our hands.

CHARLES C. STUTZ.
ROBERT F. ARNOTT.
